UNITED STATES PATENT OFFICE.

FREDERICK GEO. CRONENBERGER, OF WHITE LAKE, SOUTH DAKOTA.

TANK.

1,359,673.

Specification of Letters Patent. Patented Nov. 23, 1920.

Application filed November 22, 1919. Serial No. 340,076.

To all whom it may concern:

Be it known that I, FREDERICK G. CRONENBERGER, a citizen of the United States, residing at White Lake, in the county of Aurora and State of South Dakota, have invented a new and useful Tank, of which the following is a specification.

This invention relates to new and useful improvements in water systems, and more particularly to a system to be installed and used in rural districts, where public water systems are not in use.

The primary object of the invention is to provide a compressed air water system, which will be automatic in its operation, and one in which the tank forming a part thereof is air-tight, being constructed of concrete, thereby eliminating the use of steel structures and consequently reducing the cost of the system, to a minimum.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a longitudinal sectional view through the tank and housing forming a part of the system,

Fig. 2 illustrates a plan view of the pipe securing means, and

Fig. 3 illustrates a plan view of the tank and housing.

Referring to the drawings in detail, the reference character 5 designates the main, or supply tank of the system, the same being formed preferably of concrete, the reinforcing bars 6 being embedded in the concrete and passing around the body portion thereof.

The upper portion of the tank is concaved, and provided with a central man hole 7, which man hole is embraced by the metallic collar 8, provided with flanges 9 cooperating with the underside of the upper wall

of the tank to provide an air tight connection between the tank and the collar 8, the collar 8 acting as a support for the man hole cover 10, which is bolted to the collar 8 by means of the bolts 11 passing therethrough,

suitable packing may, however, be employed

for providing an air tight connection between the man hole cover 10 and its supporting collar 8.

Disposed adjacent the main tank 5, is a concrete housing 12, which is preferably of smaller diameter than the tank 5, the same being for the purpose of housing the pump construction and valves controlling the flow of water to and from the tank 5, the upper portion of said housing 12 being provided with an opening 13 closed by the closure 14, which opening is of a size to permit a person to examine the valves and pump construction, in the event that the same become worn, or rendered inoperative.

The housing 12 is provided with an opening 15, formed in the upper wall thereof, and an opening 16 formed in the lower wall thereof, the opening 16 being for the purpose of accommodating the pump tubing 17, the upper end of which extends to a point within the housing 12. The upper portion of the pipe 17, is embraced by a collar 18 having the lateral threaded openings 19 which receive the supporting pipes 20, each of which has connection with a supporting plate 21, at the lower end thereof, which supporting plates are secured within the bottom of the housing 12, by means of the bolts 22, embedded within the concrete of the tank, the upper end thereof extending through suitable openings in the supporting plates 21, and accommodate the nuts 23, which hold the plates 21 against displacement within the housing.

Supported above the threaded openings 19, is a coupling 24, which coupling provides means for connecting the feed pipe 25, to the pump tubing 17, one end of which extends through the concrete reinforcement 26, and into the tank 5, the pipe 27 having connection therewith, and having its discharge end disposed adjacent the bottom of the tank 5, so that water entering the tank, is fed thereto at the bottom thereof so that the water will compress air within the tank 5, which air, in its operation of the system forces the water from the tank and through the various pipes of the system.

The supply pipe 28 has communication with the pipe 25, through the coupling 29, the pipe 28 being shown as extending through an opening 30 formed in the bottom of the housing 12, the end thereof having connection with the supply pipes leading to

the house, or other building being furnished with water from the system, a check valve 31, being provided to direct the flow of water through pipe 28, and prevent the same from 5 returning to the pipe 17.

Supported in close proximity with the valve 31, is a manually controlled valve 32, operated by the valve rod 33, extending through the upper wall of the housing 12, 10 and being provided with an operating wheel 34, on the upper end thereof. It will thus be seen that when the tank is to be filled, the valve 32 is turned to permit the passage of water from pipe 17 to the tank 5, the 15 amount of water within the tank 5 being controlled by the amount of air pressure registered on the indicator 35, positioned within the housing 12, and having communication with the upper portion of the tank 5, through the pipe 36, a gage 37 being also 20 in communication with the pipe 36 and pipe 25, for indicating the level of the water within the tank 5, the usual sucker rod 38 operates in the pipe 17 for causing water 25 to be supplied to the tank 5, the sucker rod 38 having connection with any suitable power mechanism, not shown.

While I have shown a water system including concrete tank structures, it is to be 30 understood that these tanks are embedded under the ground surface, the upper portion of the tank being shown as concaved, to increase the strength thereof to better 35 resist the air pressure under which the system operates.

Having thus described the invention, what is claimed is:—

1. A water system including a tank, a housing associated with the tank, pump tubing extending into the housing, supporting pipes having connection with the pump tubing, supporting plates having connection with the supporting pipes, bolts passing through the supporting plates, said bolts extending into the structure of the housing, 40 means for securing the plates to the bolts, and means for providing communication between the tank and housing.

2. A water system including a concrete tank, said tank having a concaved upper 50 wall, a man hole cover covering an opening in the concaved upper wall, a housing associated with the tank, pump tubing extending into the housing, means for providing communication between the pump tubing and 55 bottom of the tank, a one-way valve for preventing reverse flow of water from the tank, means having communication with the upper portion of the tank for indicating the air pressure within the tank, and means for 60 supporting the upper end of the pump tubing within the housing.

In testimony that I claim the foregoing as my own, I have hereto affixed my signature in the presence of two witnesses.

FREDERICK GEO. CRONENBERGER.
